MACHINE FOR RESURFACING OIL-SURFACED ROADS

Herbert E. Moore, Red Oak, Iowa

Application July 1, 1939, Serial No. 282,569

6 Claims. (Cl. 94—40)

This invention relates to improvements in machines for resurfacing oiled surfaced roads, and more particularly to the resurfacing of graveled roads that have previously been treated with a hardening substance wherein it is at times necessary to remove the top hardened surface and relay it, due to the fact that the said surface becomes broken and full of holes.

The object of my invention is to provide a machine or device which may be drawn over the road surface by a tractor or other suitable draft device, and to break up and pulverize the hardened surface and deliver the same to a heating chamber or drum so that the oil and other substances used to harden the surface may be softened and dissolved to permit the material to be pulverized and an additional fluid for hardening the substance added if so desired, and to return the substance again to the ground surface as the machine is advanced over the same, so that the roadbed may be rapidly and cheaply resurfaced and wherein most of the old material may be utilized in the resurfacing of the roadbed.

A further object of my invention is to provide in a machine for resurfacing oiled and graveled roads, and employing a rotatably mounted drum for heating and pulverizing the old material removed from the roadbed, improved means for mounting the drum wherein it may be maintained at an inclined position relative to the horizontal, regardless of whether or not the device is being moved up or down hill, and to provide in connection therewith improved means for breaking up and gathering the top surface of the old roadbed and delivering the same to the heating drum.

A further object of my invention is to provide in a device of the class above described, improved means for breaking up or disintegrating the top of the roadbed.

A further object of my invention is to provide a resurfacing machine of the type above described wherein the entire operation of breaking up the top surface or crust and delivering the same to the heating drum may be mounted on a single truck, the parts being so arranged and constructed that the truck may be of a minimum length to permit the device to be readily handled on the ordinary road, and yet of such size that a comparatively large amount of material may be handled so that the work may be rapidly accomplished.

My invention consists in the construction, arrangement and combination of the various parts of the device, whereby the objects contemplated

are attained, as hereinafter more fully set forth, pointed out in my claims, and illustrated in the accompanying drawings, in which:

Figure 1 is a side elevation of my improved resurfacing machine;

Figure 2 is a plan view of the same;

Figure 3 is a detail sectional view taken on the line 3—3 of Figure 2;

Figure 4 is a detail sectional view taken on the line 4—4 of Figure 2, a portion of the frame work being removed to illustrate the cutters for breaking up the top surface and also the scraper for delivering said material laterally, together with the means for elevating and lowering both of said devices;

Figure 5 is a detail sectional view taken on the line 5—5 of Figure 3;

Figure 6 is an enlarged detail diagrammatical view of the delivery end of the scraper and receiving end of the first elevating conveyor, taken substantially on the line 6—6 of Figure 1;

Figure 7 is an enlarged detail sectional view taken on the line 7—7 of Figure 1.

My improved device comprises a frame member 10 having side rails 11 and transversely arranged bars 12, the rear end of the frame being supported by wheels 13, while the front end of the frame is supported by wheels 14 and an axle 15, the wheels 14 being steered by the usual steering mechanism 16 and a tongue or drawbar 17. Carried by the members 11 is an upright frame member 18 having supported on its upper end an oil tank 19.

Mounted in the members 11 near their rear ends are pivot members 20 supporting transversely arranged channel irons 21, each end of said irons 21 having upwardly and outwardly diverging brace members 22 adapted to support a frame member 23, one of the brace members 22 being supported with a gear sector 24 adapted to be operated by means of a worm gear mechanism 25, wherein the sector will cause the frame member 23 to be rocked on the pivots 20, the worm gear mechanism serving as means for locking the frame 23 in any of its adjusted positions.

Carried by the frame 23 are semi-circular frame members 26, each being provided with rollers 27 rotatably supporting a drum 28, said drum having annular tracks 29 receiving said rollers, the central portion of the drum 28 being provided with an annular gear rack 30 designed to be driven by means of a spur gear 31 mounted on the shaft 32 supported by the beams 21, the gear 31 providing means whereby the drum may be rotated by means of the shaft 32 and a sprocket

33 and a chain 51, in the manner hereinafter made clear.

Supported within the drum 28 is what I shall term a mixing drum 34, having an annular space 35 between said drums in which a flame 36 from an oil burner 37 may be projected for the purpose of heating said drum 34. Supported longitudinally through the center of the drum 34 is a mixing shaft 38 having mixing blades 39, the ends of the shaft 38 being supported by bearings 40 and 41 carried by the ends of the frame 23. The back end of the shaft 38 has a sprocket wheel 42 by means of which the said shaft may be rotated, and with it the mixing and pulverizing blades 39.

Supported longitudinally beneath the frame 10 is a shaft 43 having a sprocket wheel 44 on which is mounted a chain 45 (see Figure 1), said chain 45 being mounted on a sprocket 46 carried on the rear end of a shaft 47 extending longitudinally above the frame members 11 and terminating near their forward ends, the front end of the shaft 47 being driven by means of a belt 48 from an engine 49, thus providing means whereby the shafts 47 and 43 are driven. The shaft 43 is provided with a sprocket 50 on which is mounted a chain 51 passing over the sprocket 33 (see Figure 5), thus providing means whereby the shaft 32 may be driven, and with it the sprocket 33 and the drums 28 and 34.

Supported on one side of the frame member 23 is a shaft 52 having near its central portion a spur gear 53 adapted to mesh with the gear 30, thus providing means whereby the shaft 52 may be rotated. The rear end of the shaft 52 is provided with a sprocket 54 having a chain 55 passing over the sprocket 42 mounted on the rear end of the shaft 38, thus providing means for driving the said pulverizing and mixing shaft 38 and the blades 39.

Pivotedly supported to the back side of the axle 15 is a frame member 57 having mounted therein a shaft 58 on which is mounted a series of flat discs 59. For raising and lowering the free end of the frame 57 I have provided a worm gear mechanism 60 having a crank shaft 61 on which are mounted cranks 62, each of the cranks 62 being provided with a downwardly extending link 63 pivotally connected to one side of the frame member 57, the said worm gear device 60 having a crank shaft 64 by means of which the worm 65 may be rotated and the shaft 61 operated. This provides means whereby the discs 59 may be elevated or lowered, and also provides means whereby downward pressure may be applied to the discs so that substantially the entire weight of the front end of the frame 10 may be carried by said discs, thus providing means whereby the discs may be caused to enter the very hard top surface of a gravelled road, causing the said top surface to be sliced and otherwise loosened.

It is sometimes desirable to rotate the discs 59 as they are being advanced through the earth, and to rotate the discs in an anti-clockwise direction as viewed in Figures 1 and 4. To accomplish rotation of the discs I have provided on the shaft 58 a bevel gear 103 which is in mesh with a bevel gear 104 mounted on one end of a shaft 105, the other end of said shaft being provided with a bevel gear 106 meshing with a bevel gear 107 mounted on a transversely arranged shaft 108 passing through the pivot center of the frame 57. The shaft 108 is driven by means of a bevel-gear 109 mounted on the shaft 47, which is in mesh with a bevel-gear 110 mounted on the upper end of a shaft 111 having a bevel-gear 112 on its lower end, said bevel-gear meshing with a

5 gear 113 on the shaft 108, thus providing means whereby the discs 59 may be rotated when so desired, to assist in cutting the hardened surface and also for lifting small stones and similar substances out of the hardened surface rather than tending to force them into the surface as would be the case if the discs were rotated in a clockwise direction or having their peripheries travel with the surface as the discs are advanced. The 10 rotation of the discs also tends to produce a draw-cut effect. Suitable means not shown is provided for causing the discs to become operative or inoperative at the will of the operator.

A burner 114 is provided for heating the tank 19, if so desired, and an additional fuel tank 115 is provided for supplying fuel to the burner 114.

Supported in the frame members 11, back of the discs 59, I have provided a shaft 66 on which is pivotally mounted beams 67, said beams being adapted to support a scraper blade 68 which is 20 designed to be moved back of the discs 59, and to cut loose and gather the material loosened by said discs, and to convey it transversely to the inner end 69 of the blade 68, the outer end of the blade 68 being provided with a forwardly extending partition or plate 70 for the purpose of preventing material gathered by the blade 68 from passing around the outer end of the said blade.

30 A worm gear 71 and a worm 72 provide means for oscillating a rock shaft 73, having links 74 connected with the beams 67. A shaft 75 provides means for actuating the worm 72 by means of a crank 76. Thus means is provided for raising and lowering the blade 68, also for applying pressure to said blade if so desired.

Supported adjacent to the delivery end 69 of the plate 68 I have provided an elevating conveyor 77 operated from a shaft 78 at its upper end, said shaft being driven by means of a sprocket wheel 79, a chain 80, which in turn is driven from a sprocket 81, and mitre-gears 82, one of said mitre-gears being mounted on the shaft 47. A link 83 is provided having one end connected to the inner one of the beams 67 and the other connected to the inner side of the conveyor 77, the upper end of said conveyor 77 being pivotally mounted about the shaft 78 so that as the beams 67 are elevated and lowered, the lower end of the conveyor 77 will also be elevated and lowered, the lower end of the conveyor 77 being so located as to gather up material from the inner end of the blade 68.

55 The inner end of the frame 23 is provided with upwardly and forwardly extending brackets 84 having pivotally mounted in their upper ends a conveyor 85, the lower end of said conveyor 85 being pivotally connected to links 86 carried by the frame members 11. A trough 87 is provided for conveying material from the upper end of the conveyor 77 to the lower end of the conveyor 85, a trough 88 being provided for conveying material from the upper end of the conveyor 85 to the interior of the drum 34. The conveyor 85 is driven from a shaft 89 rotatably mounted in the upper end of the brackets 84. One end of the shaft 89 is provided with a bevel-gear 90 designed to mesh with a bevel-gear 91 carried by one end of a shaft 92, the other end of the shaft 92 having a sprocket 93 carrying a chain 94 driven from a sprocket 95 supported on the forward end of the shaft 52. Thus, means is provided for driving the elevating conveyor 85.

60 Since the lower end of the conveyor 85 is pivotally supported on the links 86 it will readily be seen that the frame 23 may be tilted, and when

so tilted a slight longitudinal movement will be imparted to the said conveyor 85, at the same time permitting the conveyor to always be in operative relation with the drum 34 when in any of its inclined positions of movement.

A pipe 96 is provided for delivering oil from the tank 19 to the interior of the drum 34 whenever desired. A tank 97 provides means for furnishing fuel to the burner 37 by means of a pipe 98, a control valve not shown being provided in each of these pipes controlling the amount of fuel and oil as desired.

Supported on the rear end of the frame members 11 is a transversely arranged conveyor 99 adapted to receive material from the delivery end of the drum 34 to convey it transversely to one side of the machine if so desired, the conveyor being operated by means of a belt 100 from the shaft 43, the conveyor 99 being carried by brackets 101 which are detachably connected with the frame members 11 by bolts 102 in such a manner that the conveyor 99 may be removed if so desired, and when removed, material from the drum 34 will be delivered directly to the ground surface beneath the rear end of the drums 34 and 28.

By this arrangement it will be seen that I have provided means whereby the hardened top surface of an oiled or otherwise treated gravelled road may be sliced or cut by means of the discs 59, then scraped and gathered and moved inwardly to the lower end of the conveyor 77 where it will then be elevated upwardly and forwardly, and thence delivered transversely by the trough 87 to the lower end of the conveyor 85, and further elevated upwardly and rearwardly and delivered to the trough 88, and from there to the interior of the drum 34, this drum being continuously rotated in one direction, either with or without heat applied into the space 35. The blades 39 are also continuously rotated to break up and pulverize chunks of material delivered to the drum, the application of heat greatly assisting in the disintegration of the lumps so that the material delivered at the rear end of the drum 34 will be mixed and heated in the proper condition to be again applied to the road surface. This material may be delivered directly to the ground below the discharge end of the cylinder, or it may be conveyed to one side of a road, if so desired, at which time additional finishing material may be added if it is deemed necessary, after which the material may then be spread in the usual manner.

The worm gear mechanism 25 provides means whereby the inclination of the drum may be varied so as to control the rate of flow from the forward end of the drum to its rearward end at the will of the operator, and regardless of whether or not the machine is being advanced up or down hill, thus providing means whereby the speed of the advance of the material through the drum may be accurately controlled so that the material will receive the desired amount of mixing and pulverization before being delivered to the ground surface.

By providing a forwardly and upwardly inclined conveyor and a rearwardly and upwardly inclined conveyor I have provided means whereby the length of the entire machine may be considerably decreased over what would be necessary if the entire conveyor extended in one direction, and provides means whereby the cutter 59 may be operated near the front end of the conveyor and the gathering and scraping near the central por-

tion of the frame, which I find to be a very desirable arrangement.

I claim as my invention:

1. In a device of the class described, the combination of a portable frame, an auxiliary frame pivotally connected to the portable frame and extending rearwardly of its pivot member, a transversely arranged shaft carried by the rear end of said auxiliary frame, a series of flat discs carried by said shaft, means for elevating and lowering the rear end of said auxiliary frame, said elevating and lowering means including means for applying pressure to said discs, a scraping blade supported back of said disc adapted to gather material sliced by said disc and to convey it transversely to one end of said blade, means for raising and lowering said blade, a mixing chamber, means for pulverizing material within said mixing chamber, means for applying heat thereto, and means for delivering material from the delivery end of said scraper to the inner end of said mixing chamber.

2. In a device of the class described, a portable frame, a drum-supporting frame pivoted to swing about a transverse axis in either direction past a normal inclined position, a pulverizing and heating drum open at each end, the upper end being adapted to receive scarified material from the road bed over which the frame is advanced, to be reconditioned therein, means supporting said drum on said drum-supporting frame to rotate about a longitudinal axis, a mixer within said drum, manually operated means carried by said portable frame for tilting the drum-supporting frame, means for locking said frame to one of a number of adjusted positions whereby the longitudinal angle of the drum may be tilted in opposite directions relative to a normally rearwardly and downwardly inclined position to regulate the flow of material longitudinally through said drum by gravity as it is rotated, regardless of the inclination of the road bed over which the machine is advanced, means for rotating said drum, and means for actuating said pulverizing means.

3. In a road resurfacing machine, a portable frame, a tiltable drum-supporting frame carried thereby, a longitudinally arranged pulverizing and heating drum open at each end to provide receiving and delivery ends carried by said tiltable frame to permit material to be passed continuously therethrough as the drum is rotated about its longitudinal axis, manually controlled means for tilting the angle of the longitudinal axis of said drum in opposite directions from a normal inclined position relative to the horizontal, to regulate the rate of flow of material through said drum by gravity, regardless of the inclination of the road bed over which the machine is advanced, scarifying means adjustably mounted on the front end of said frame for loosening the top portion of the road bed over which the machine is advanced, an inclined scraper blade supported at the rear end of said scarifying means, an upwardly and rearwardly inclined conveyor having its outer end pivoted to and carried by said portable frame and its upper end supported to deliver material into the receiving end of said drum, conveying means operatively connecting the upper end of said inclined conveyor with the drum supporting frame to cause the delivery end of the conveyor to be maintained in operative relation with the drum at all times when the drum is at any one of its tilted positions of movement, a second conveyor carried by said frame extending downwardly and rearwardly from a

point near the pivoted end of the first conveyor to position near the road bed to receive scarified material from the delivery end of said earth inclined scraper blade conveying means for delivering material from the second conveyor to the first conveyor, means for driving said conveyors as the machine is advanced, whereby the loosened material may be delivered to and through said pulverizing and heating drum and again to the road bed, in a continuous manner.

4. In a road resurfacing machine, a portable frame, a tilttable drum-supporting frame carried thereby, a longitudinally arranged pulverizing and heating drum open at each end to provide receiving and delivery ends carried by said tilttable frame to permit material to be passed continuously therethrough as the drum is rotated about its longitudinal axis, manually controlled means for tilting the angle of the longitudinal axis of said drum in opposite directions from a normal inclined position relative to the horizontal, to regulate the rate of flow of material through said drum by gravity, regardless of the inclination of the road bed over which the machine is advanced, scarifying means for loosening the top portion of the road bed over which the machine is advanced, an inclined scraper blade supported by said frame for gathering said scarified material; an upwardly and rearwardly inclined conveyor having its outer end pivoted to and carried by said portable frame and its upper end supported to deliver material into the receiving end of said drum, conveying means operatively connecting the upper end of said inclined conveyor with the drum-supporting frame to cause the delivery end of the conveyor to be maintained in operative relation with the drum at all times when the drum is at any one of its tilted positions of movement, a second conveyor carried by said frame extending downwardly and rearwardly from a point near the pivoted end of the first conveyor to position near the road bed to receive material from the delivery end of said scraper blade, conveying means for delivering material from the second conveyor to the first conveyor, means for driving said conveyors as the machine is advanced, a conveyor carried by the frame for receiving material from said drum and delivering it laterally to one side of a road bed, and means for driving the last conveyor; whereby the loosened material may be delivered from the road bed continuously to and through said drum to be pulverized, heated and conditioned for resurfacing, and delivered to one side of the road bed in a continuous manner, and whereby the rate of flow of material through said

drum by gravity may be regulated at the will of the operator.

5. In a device of the class described, the combination of a portable frame, an auxiliary frame pivotally connected to the portable frame and extending rearwardly of its pivot member, a transversely arranged shaft carried by the rear end of said auxiliary frame, a series of flat discs carried by said shaft, means for elevating and lowering the rear end of said auxiliary frame, 10 said elevating and lowering means including means for applying pressure to said discs, a scraping blade supported back of said disc adapted to gather material sliced by said disc and to 15 convey it transversely to one end of said blade, means for raising and lowering said blade, a mixing chamber, means for pulverizing material within said mixing chamber, means for applying heat thereto, and means for delivering material 20 from the delivery end of said scraper to the inner end of said mixing chamber, and a conveyor carried by the delivery end of the supporting frame for conveying material delivered from said drum to one side of a road bed as the machine as advanced.

6. In a device of the class described, a portable frame, a drum-supporting frame pivoted to swing about a transverse axis, a pulverizing and heating drum open at each end to receive material at one end and deliver it to the other end, means supporting said drum within said drum-supporting frame to rotate about a longitudinal axis, a pulverizer within said drum, manually operated means carried by said portable frame for tilting the drum-supporting frame and the drum carried thereby, means for locking said frame to one of a number of tilted positions whereby the longitudinal angle of the drum may be varied to regulate the flow of material through said drum by 30 gravity as it is rotated, scarifying means adjustably supported by the front end of said frame, an inclined blade supported at the rear of said scarifying means, and an elevating and conveying means carried by the portable frame for delivering the scarified material from the scraper blade to the inlet end of the drum, whereby material may be loosened from a road bed and delivered continuously to said mixing drum at any of its adjusted inclined positions of movement, 35 and whereby the rate of flow of material through said drum by gravity may be regulated at the will of the operator, regardless of the inclination of the road bed over which the machine is advanced.

55 HERBERT E. MOORE.
